CHAUNCEY R. DANA, OF SAN FRANCISCO, CALIFORNIA.

PIPE-VISE.

1,242,426.

Specification of Letters Patent.

Patented Oct. 9, 1917.

Application filed July 31, 1916. Serial No. 112,285.

To all whom it may concern:

Be it known that I, CHAUNCEY R. DANA, a citizen of the United States, residing at the city and county of San Francisco and State of California, have invented new and useful Improvements in Pipe-Vises, of which the following is a specification.

This invention relates to a pipe vise.

One of the objects of the present invention is to provide a simple, compact, portable pipe vise particularly adapted for use by plumbers and like mechanics, and also to provide a structure which will permit it to be quickly and easily attached to a convenient support. Another object of the invention is to provide a double acting mechanism for adjusting the position of the gripping jaws and for moving same into clamping action, when required.

20 The invention consists of the parts and the construction and combination of parts as hereinafter more fully described and claimed, having reference to the accompanying drawings, in which—

25 Figure 1 is a side elevation of a vise.

Fig. 2 is a view of the front end of the vise.

Fig. 3 is a cross section on line 3—3 of Fig. 1.

30 Fig. 4 is a cross section on line 4—4 of Fig. 1.

Fig. 5 is a plan view of the vise.

Fig. 6 is a central, longitudinal section of the vise on line 6—6 of Fig. 5.

35 Referring to the drawings in detail, A indicates, in general, the base of the vise; 2 a pair of stationary pivotally mounted jaws; and 3 a movable coöperating pivotally mounted jaw. The base, while forming an integral unit, consists of a pair of inter-spaced side plates 4 and a pair of end sections 5 and 6. Each stationary jaw is offset, as at 7, to permit the jaw portion to rest on top of the side plates and the lower part

45 of each jaw is extended to form a shank 8 which permits the same to be pivotally secured to the side plates by means of the bolts 9. The movable jaw 3 is also offset, as at 10, to engage the upper face of the side plates 4, and the lower part is provided with a shank extension 11, which is disposed in the space formed between the plates 4. The coöperating faces of both the movable and stationary jaws are provided with teeth,

such as indicated at 12, and similar teeth 13 may also be formed in the top faces of the plates 4, as shown.

The approximately stationary jaw 2 and the movable or gripping jaw 3, each having oppositely extended members 11 and 8, pivoted at a distance apart and behind the jaws, and the offsets of the jaws being supported upon the upper faces of the side plates 4, it will be manifest that the jaws being thus pivoted and supported are free to adjust their faces automatically so as to grip any irregular surface or curvature of the article to be held, and while allowing such adjustment will be prevented by the off-set shoulders from being forced downward. The distance of the pivots from the faces of the jaws insures the approximate parallelism of the jaws.

Slidably mounted in the rear end section of the base, indicated at 5, is a bushing 14, one end of which is headed, as at 15, to permit the insertion of a spring 16 between the head and the base end 5. Pivotally mounted between the side plates, as at 16', adjacent to the end section 5 and the head 15 formed on the bushing 14, is a lever 17. The lower end of this lever is fork-shaped to straddle a screw rod 18, and cam members 19 are formed adjacent to the pivot 16' to engage the headed bushing, as will hereinafter be described.

The screw rod 18 passes freely through the end section 5 of the base and the bushing 14 and also the forked end of the lever. The inner end of the rod is pivotally secured, by means of a pin 19', to the rear end of the shank 11, forming a part of the movable jaw 3, while the outer end of the screw rod, projecting through the base, is provided with a nut 20 to permit longitudinal movement of the rod and connected jaw 3.

Pivotally mounted in the forward end of the base, as at 21, is a downwardly extending gripping jaw 22, the inner face of which is serrated or provided with teeth, such as shown at 23. This jaw may be swung about the pivot to assume the full line position shown in Figs. 1 and 6 and may also be folded or swung about the pivot to assume the dotted line position, indicated at 24, as will hereinafter be described.

The vise here shown is particularly constructed for the use of plumbers and like

mechanics and is, therefore, constructed to produce as compact and light a structure as possible.

In operation, if it is desired to use the vise, it is only necessary to lower the gripping jaw 22. The vise as a whole is then placed on a suitable support and moved inwardly on same until the front edge of the support is engaged by the lowered jaw 22. 5 This secures the forward end of the vise and is in many instances sufficient. If it is desired to further secure the base, it is only necessary to drive a couple of nails or bolts through lugs 25 formed on the rear end of the base. 10 The lever 17, under normal conditions, will assume the position shown in Figs. 1 and 5. This permits the nut 20 to be turned to adjust the spacing between the stationary 15 jaws 2 and the movable jaw 3. A pipe or other object to be gripped is then placed between the jaws and is here secured by throwing the lever about the pivot in the direction of arrow *a* (see also Fig. 6). This will cause the cam members 19 to engage the headed end of the bushing and the bushing in turn will engage the inner face of the nut 20, thus forcing the nut and screw rod, with the connected jaw 3, into gripping action or 20 toward the stationary jaw members 2. The combined cam and lever action here provided permits sufficient movement of the jaw 3 to securely grip a pipe placed between the jaws and also permits a quick release, 25 when it is desired to remove the same. The spring 16 always holds the headed end of the bushing in engagement with the cam members 19, in this manner permitting the nut 20 to be freely turned without any interference by the bushing 14. The side plates 30 of the base are provided with a plurality of alined tapped holes 30 for the reception of the bolts 9. This permits the stationary 35 jaws to be moved longitudinally along the base to assume various fixed positions, thus permitting pipes of considerable sizes to be handled.

The pin 19, which secures the screw rod to the shank 11, does not only extend 40 through the shank but also through slots 31 formed in the side plates 4. This forms a perfect guide for the forward end of the shank, it also permits a pivotal movement of the jaw and co-operates with the offset sections 10 formed on the jaw to rigidly support and guide the jaw when moved for adjustment.

The device as a whole is simple and compact in construction and as both the lever 17 and the lower gripping jaw 22 may be folded flat, with relation to the base, it can readily be seen that it will require a comparatively small space and may, therefore, be carried in a mechanic's tool grip, if desired.

The adjustment of the jaw 3 produced by means of the nut 20 and the screw rod 18, together with the clamping action of the lever 17 and co-operating cams 19, does not only permit a quicker release or gripping engagement, with relation to the object to be held, but also permits objects of various sizes and shapes to be handled. The teeth provided on the co-operating faces of the jaws are preferably turned in a downward direction as here shown. This positively grips a pipe, when handled, and keeps same from turning in either direction and is, furthermore, assisted by the teeth 13 formed in the top edges of the side plates. 75

The materials and finish of the several parts of the device are such as the experience and judgment of the manufacturer may dictate.

I wish it understood that various changes in form, proportions and minor details of construction may be resorted to within the scope of the appended claims, and that I do not wish to limit myself to the specific design and construction here shown. 80

Having thus described my invention, what I claim and desire to secure by Letters Patent is—

1. In a pipe vise, a frame, a pair of pivotally mounted, normally stationary gripping jaws on the frame, a movable pivotally mounted gripping jaw, a screw mechanism for adjusting the position of the movable jaw, and a cam lever operable independently of the screw mechanism for moving the jaw. 95

2. In a pipe vise, a frame, a pair of pivotally mounted, normally stationary gripping jaws on the frame, a movable pivotally mounted gripping jaw, a screw mechanism for adjusting the position of the movable jaw, a cam lever operable independently of the screw mechanism for moving the jaw, and means for moving the stationary jaws longitudinally of the frame to assume fixed positions. 105

3. A pipe vise comprising an elongated, centrally slotted frame, a pair of pivotally mounted, normally stationary gripping jaws secured on said frame, a co-operating gripping jaw, a screw rod extending through one end of the frame and connected with said jaw, a nut on the rod engageable with the end of the frame to permit movement of the screw rod and connected jaw, and a cam lever operable in conjunction with the nut to move the rod and jaw. 115

4. A pipe vise comprising an elongated, centrally slotted frame, a pair of normally stationary gripping jaws secured on said frame, a co-operating gripping jaw, a screw rod extending through one end of the frame and connected with said jaw, a nut on the rod engageable with the end of the frame to permit movement of the screw rod and connected jaw, a headed bushing slidably 125

mounted on the screw rod and extending through the frame, said bushing being engageable at one end with the nut, and a cam lever pivotally mounted in the frame engageable with the headed end of the bushing.

5. A pipe vise comprising an elongated, centrally slotted frame, a pair of normally stationary gripping jaws secured on said 10 frame, a coöperating gripping jaw, a screw rod extending through one end of the frame and connected with said jaw, a nut on the rod engageable with the end of the frame to permit movement of the screw rod and 15 connected jaw, a headed bushing slidably mounted on the screw rod and extending through the frame, said bushing being engageable at one end with the nut, a cam lever pivotally mounted in the frame engageable 20 with the headed end of the bushing, a spring interposed between the headed end of the bushing and the end of the frame, and teeth formed on the top edge of the frame to co-operate with the gripping jaws.

6. A pipe vise comprising a frame, a stationary gripping jaw and a coöperating slideable gripping jaw, said jaws being pivotally mounted at one end, a screw rod extending through the frame connected with the slideable jaw, an adjusting nut on said rod to move the jaw connected therewith, and a cam lever fulcrumed at a fixed point in the frame to impart a longitudinal movement to the nut, rod and connected jaw.

7. A pipe vise comprising a frame, a stationary jaw and a coöperating slideable jaw, said jaws being pivotally mounted at one end, an adjustable screw mechanism to control the position of the movable jaw, and a cam lever pivotally mounted in the frame to impart movement to said jaw.

In testimony whereof I have hereunto set my hand in the presence of two subscribing witnesses.
